UNITED STATES PATENT OFFICE.

JOHN P. DINEEN, OF BOMBAY, INDIA.

RAILROAD-CROSSING ALARM.

Application filed March 23, 1927. Serial No. 177,794.

This invention relates to railway crossing signals and pertains particularly to a train operated signal.

The primary object of this invention, is to provide, in a manner as hereinafter set forth, a mechanically operated signal designed particularly for use in such isolated crossings or curves where the equipment for a more elaborate signal structure could not 10 be had.

Another object of this invention, is to provide, in a manner as hereinafter set, a mechanical crossing signal for railway lines adapted to be operated by the passage of the 15 train wheel flanges over an operated member to actuate a signal element.

Still another object of the invention is to provide, in a manner as hereinafter set forth, a railway crossing signal designed to 20 be set in operation, and having two operating parts which will positively and reliably act to actuate a signal element.

A further and final object of this invention is to provide a signal of the above described 25 character which will be strong and durable, having little or no up keep cost and comparatively inexpensive to manufacture and install.

Other objects and advantages of the invention will become apparent as the description 30 of the same proceeds, and the invention will be best understood from a consideration of the following detailed description taken in connection with the accompanying drawings forming a part of this specification, 35 with the understanding however, that the invention is not confined to any strict conformity with the showing of the drawings, but may be changed or modified so long as such changes or modifications mark no material departure from the salient features of 40 the invention as expressed in the appended claims.

In the drawings, 45 Figure 1 is a view taken transversely of a railway track and through the longitudinal center of the signal structure embodying this invention, which structure is arranged between the rails of the track.

50 Figure 2 is a plan view of the track way, and the structure embodying this invention, a portion of the signal structure being shown in horizontal section.

Figure 3 is a section taken upon the line 55 3-3 of Figure 2.

Figure 4 shows an alarm bell supporting post in side elevation, showing the alarm set to carry thereon.

Figure 5 is a front elevation of the post and alarm structure shown in Figure 4. 60

Referring now to the drawings in detail wherein like numerals of reference indicate corresponding parts throughout the several views, the numerals 1 indicate the rails of a track way, between which rails the signal 65 operating mechanism is arranged.

The signal operating structure comprises a base 2 having a housing 3 mounted thereon, one end wall of the housing being provided with the vertical slot 4 while the opposite end wall is provided at the lower portion with the aperture 5.

Extending longitudinally through the housing 3 is a signal operating beam 6 one end of which projects through the slot 4. 75 This beam is pivotally mounted within the housing 3 adjacent that end which extends through the slot 4, upon the upstanding bearing bracket 7 and mounted upon the floor 2 of the housing beneath the inner end of the beam 6 is a pair of pulley wheels 8. Each end of the beam 6 has an aperture formed therethrough as indicated by the numerals 9 and 10.

The housing structure 3 is so mounted 80 between the rails that the end walls through which the slot is formed is arranged in close proximity to one side of one of the rails 1, as shown in Figures 1 and 2.

Arranged longitudinally of and upon the 85 inner side of the last mentioned rail between the rail and the adjacent end of the housing 3, is an elongated trip platform indicated generally by the numeral 11.

This trip platform comprises an elongated 90 central portion 12 and the downwardly inclined end portions 13. The central portion 12 of the tripping platform has each end thereof supported by the helical springs 14 which are mounted upon appropriate face 100 plates 15 carried by the adjacent end of the housing. These springs 14 maintain the central portion 12 of the tripping platform in substantially the same plane as the top of the head 16 of the adjacent rail. From this it 105 will be seen that the inclined end portions 13 of the tripping platform central portion 12 extend downwardly a substantial distance beneath the rail head 16 and when a car wheel passes along this portion of the rail 110

the flange of the wheel will gradually ride upon the platform 11 and depress the same against the tension of the springs 14.

The central under portion of the platform 5 central portion 12 is provided with the depending substantially U-shaped saddle indicated generally by the numeral 17, this saddle comprising the upright arms 18 and the cross connecting portion 19. This cross connecting portion or yoke 19 passes through the aperture 10 in the adjacent end of the beam 6 and thus, as will be readily seen, when the platform is depressed the adjacent end of the beam 6 will also be depressed while 10 the free inner end will be swung upwardly. Owing to the fact that the fulcrum point of the beam 6 is near the outer end upon which the pressure is applied, the inner end 15 will swing to an arc of greater degree than the depressed outer end.

The free outer end of each of the inclined portions 13 of the platform 11 carry downwardly extending arms 20 which are appropriately shaped to change the lower ends 25 thereof beyond the adjacent edge of the rail base 21 and the lower end of each of these arms is provided with inwardly extending fingers 22 which normally engages beneath the rail base when the platform is in set position. These fingers 22 prevent one end 30 of the platform from swinging upwardly when a car wheel forces the other end down and thus prevents undue strain from being placed upon the beam 6.

Secured to the aperture 9 at the free end 35 of the 6, are the ends of a pair of pull cords 23 each of which extends beneath a pulley 8 and runs to one side of the track to a signal structure such as that shown in Figures 40 4 and 5. These signal structures are arranged one on each side of the track at a crossing and, as above explained, each has one of the pull cords 23 running thereto.

Each of the signal structures comprises a 45 supporting post 24 carrying a bracket structure 25 formed of a pair of outwardly extending spaced parallel arms 26 having apertures 26'. Arranged vertically between the outer ends of the arms 26 is an elongated bell handle 27 having a bearing sleeve 28 formed integral therewith and extending transversely thereof through which sleeve a 50 supporting bolt 29, passes for engagement to support the bell handle therebetween.

The lower end of the actuating handle 55 27 carries a bell 29 thereon while the upper end of the handle is provided with an aperture 30 in which aperture one end of a spring 31 is connected, the other end of which spring 60 is attached to the adjacent post as indicated at 32.

This spring 31 maintains the bell handle 27 normally in vertical position. Or in other words, causes the bell handle 27 to 65 quickly return to a vertical position when

swung from such position by the pole upon the cable 23.

Associated with the bracket 25 is an insulation casing having brackets 33 and carrying therein a pair of contact points 34 70 which form the terminals of a broken light signal circuit, the adjacent ends of the lines of which are indicated by the numeral 35.

A contact plate 36 is reciprocally mounted within the casing, the stem 36' being drawn back by the spring 37, surrounding and engaging the stem in such position that when the upper end of the handle 27 is swung inwardly contact will be made by the member 36 between the points 34, thus completing the circuit for a light line. In this manner an electric light signal may also be employed in conjunction with the bell signal as shown and the light signal will be energized simultaneously with the sounding 85 of the bell. It will be seen however, that if the light signal should for any reason become inoperative, the bell signal will continue to operate.

From the foregoing description, it will be readily seen that the signal device herewith provided is of simple but reliable construction, and will effectively operate each time a car wheel passes over the tripping platform 11 in its progress along the rail adjacent to which the platform is mounted.

Having thus described my invention, what I claim is:

1. In a railway crossing signal of the character set forth, a beam member designed to be mounted intermediate its ends adjacent and at right angles to a track rail, a platform mounted upon that end of the beam lying adjacent said rail and designed to have the top of the central portion thereof lie flush with the top of the rail, resilient supporting means for said platform to normally maintain the same in set position, a swinging signal element and a pull cord connecting said signal element with the other end of said beam, said platform having each end thereof extending at an inclination downwardly to set up an inclined surface for the initial contact of a car wheel flange with the platform.

2. In a railway crossing signal of the character set forth, a beam member designed to be mounted intermediate its ends adjacent and at right angles to a track rail, a platform mounted upon that end of the beam lying adjacent said rail and designed to have the top of the central portion thereof lie flush with the top of the rail, resilient supporting means for said platform to normally maintain the same in set position, a swinging signal element, a pull cord connecting said signal element with the other end of said beam, and means carried by said platform at each end thereof for engagement beneath the adjacent rail to prevent 120 125 130

one end of the platform from swinging upwardly when a car wheel flange depresses the opposite end.

3. In a railway crossing signal of the character set forth, a beam member designed to be mounted intermediate its ends adjacent and at right angles to a track rail, a platform mounted upon that end of the beam lying adjacent said rail and designed to have 10 the top of the central portion thereof lie flush with the top of the rail, resilient supporting means for said platform to normally maintain the same in set position, a swinging signal element and a pull cord connecting said signal element with the other end of said beam, said platform having each 15 end thereof extending at an inclination downwardly to set up an inclined surface for the initial contact of a car wheel flange 20 with the platform, means extending downwardly from the free end of each of said inclined portions for engagement beneath the adjacent rail to prevent one end of the platform structure from swinging upwardly 25 upon contact with the car wheel flange of the opposite end thereof.

4. In a railway crossing signal of the character set forth a supporting base structure designed to be arranged between the rails of 30 a track and having one end adjacent one of said rails, an upstanding bearing carried by said base, a swinging beam member mounted adjacent one end upon said bearing, said adjacent end being arranged in close proximity 35 to the inner side of the adjacent rail, a tripping platform pivotally mounted upon said beam end, means for normally maintaining said platform in substantially the same plane as the head of said rail, a swinging signal 40 element designed to be mounted at one side of said crossing, and a pull cord connecting said swinging element with the other end of said beam, to impart motion to the signal upon the passage of a car wheel flange over 45 said platform.

5. In a railway crossing signal of the character set forth, a supporting base structure designed to be arranged between the rails of a track and having one end adjacent 50 one of said rails, an upstanding bearing carried by said base, a swinging beam member mounted adjacent one end upon said bearing, said adjacent end being arranged in close proximity to the inner side of the 55 adjacent rail, a tripping platform pivotally mounted upon said beam end, means for nor-

mally maintaining said platform in substantially the same plane as the head of said rail, a swinging signal element designed to be mounted at one side of said crossing, a 60 pull cord connecting said swinging element with the other end of said beam, to impart motion to the signal upon the passage of a car wheel flange over said platform, and means carried by said swinging signal element whereby an electrical contact may be 65 made to cause a circuit for the operation of a light signal.

6. A railway signal including a trip element designed to be engaged by a train 70 wheel, and a pull cord operated by said trip; a supporting structure, a normally vertical arm carried by said supporting structure and engaged by said pull cord, resilient means normally maintaining said swinging arm in 75 vertical position, an electric signal device including a pair of normally spaced contacts, and a spring controlled reciprocal circuit closing element adapted to connect said contacts and arranged in position for engagement by said swinging arm when the same is actuated to bring about the closing of an 80 electric circuit through the actuation of said reciprocal circuit closing element.

7. In a railway signal device, including a 85 train controlled tripping element and a pull cord actuated thereby; a supporting structure, an arm carried by said supporting structure, a swinging arm carried upon said first mentioned arm and designed to have 90 said pull cord connected therewith, resilient means controlling said swinging arm for normally maintaining the same in vertical position, a switch structure adjustably mounted upon said first mentioned arm adjacent the swinging arm comprising a casing 95 having a pair of spaced electrical contacts mounted therein and controlling a signal circuit, a reciprocal electric current conducting element within said casing adapted to bridge said contacts for closing said circuit, resilient means normally maintaining said reciprocal current conducting element free from engagement with said contacts, and means whereby upon the actuation 100 of said swinging arm said reciprocal element will be moved to close a circuit between said contact points for the energization of the signal.

In testimony whereof I affix my signature.

JOHN P. DINEEN.
